(57) **CLAIM**

The ornamental design for a cookware article, as shown and described.

DESCRIPTION

FIG. 1 is a front perspective view of a cookware article showing our new design;

FIG. 2 is a top plan view of the cookware article;

FIG. 3 is a bottom plan view of the cookware article;

FIG. 4 is a front elevational view of the cookware article;

FIG. 5 is a rear elevational view of the cookware article;

FIG. 6 is a left side elevational view of the cookware article;

FIG. 7 is a right side elevational view of the cookware article;

FIG. 8 is a view similar to FIG. 1 but with additional broken lines; and,

FIG. 9 is a view similar to FIG. 4 but with additional broken lines.

The broken lines in FIGS. 8 and 9 show unclaimed environmental structure that forms no part of the claimed design, which unclaimed environmental structure includes a fire pit and a stand for supporting the cookware article.

The surface shadings and contour lines shown in FIGS. 1-9 represent the three-dimensional character and contour of the cookware article, and are not intended to limit the cookware article to any particular materials, colors, or surface decorations. The different surface shadings are used to indicate contrasting materials.
